TEMPER SCREW AND OPERATING MEANS

Filed April 2, 1921

2 Sheets-Sheet 2

Inventor:
Leslie F. Wright.

By James T. Walker,
his Attorney.

UNITED STATES PATENT OFFICE.

LESLIE E. WRIGHT, OF LOS ANGELES, CALIFORNIA, ASSIGNOR TO FRED L. WRIGHT,
OF LOS ANGELES, CALIFORNIA.

TEMPER SCREW AND OPERATING MEANS.

Application filed April 2, 1921. Serial No. 458,156.

To all whom it may concern:

Be it known that I, LESLIE E. WRIGHT, a citizen of the United States, residing at Los Angeles, in the county of Los Angeles, and State of California, have invented new and useful Improvements in Temper Screws and Operating Means; and the following is such a full, clear, and exact disclosure of the invention that anyone skilled in the art to 10 which it appertains may make and use the same.

My present invention relates to temper screws, of the type commonly used in connection with well drilling apparatus, to feed 15 out the cable or line, supporting the drill bit in the well, during the drilling operation.

As is well known, in this class of work, the temper screw is carried by the free end 20 of the walking beam, being pivotally mounted thereon on trunnions or the like, and carrying at its lower end a suitable clamp for engaging a line or cable extending into the bore to support the drill bit.

25 In ordinary practice the pivotal point of the walking beam is some twelve to fifteen feet above the working floor of the rig; the frame of the temper screw, of the type now in general use, being from five to seven feet 30 in length, and the main screw which is operable therein, a corresponding length; therefore it is necessary for a workman to stand on a stepladder, or the like, resting upon the rig floor, to reach the lower end of 35 the frame, to operate the yoke screw and cross bar for feeding out the main screw. This arrangement is inconvenient and unhandy, as it requires the workman to operate the yoke screw with one hand, to release 40 the clamping effect of the thread box, and to operate the cross bar with the other hand, to turn the main screw through the thread box while it is unclamped, and to again tighten the yoke screw after turning 45 the main screw. Furthermore, as the main screw can ordinarily only be turned immediately after the drill bit has struck the bottom of the bore, and when the tension is off the line, the workman must act quickly to make 50 even a quarter of a turn of the main screw.

Also, there is some danger attached to operating this old type of temper screw. In case the line becomes twisted in the bore, releasing of the yoke screw permits the main 55 screw to swing around quickly, resulting in

the cross bar very often striking the workman.

Having the aforementioned objectionable features in mind, I have designed and perfected the herein described temper screw arrangement to overcome them; resulting in a structure which is conducive to more simple, efficient and accurate operation, and obviating any possibility of injury to the workman. 60

To accomplish these results I provide a temper screw wherein the main screw is revolvably suspended from one end in a T-bearing, pivotally supported on the walking beam, and wherein the thread box is placed 65 at the upper end of the frame, so the frame is movable relative to the screw, by rotation of the latter, to feed out the line; the line in this case being carried by the frame. I also provide a suitable mechanism, carried 70 on the walking beam, for rotating the screw; this mechanism being manually operable from the derrick floor.

Also, with my improved temper screw, the main screw can be quickly rotated to return 80 the thread box and the frame to the upper end thereof, to repeat the drilling operation, thereby obviating the tedious work of performing this function in connection with the old style of screws. 85

The merits of my invention will be more fully set forth in the following detail description, reference being made therein to the accompanying drawings, forming a part thereof, in which I have illustrated its preferred specific embodiment, and in which— 90

Fig. 1 is a fragmentary elevation of the lower end of a typical drilling rig showing a practical application of my device; Fig. 2 is an enlarged front elevation of my improved temper screw; Fig. 3 is a fragmentary elevation of a typical walking beam and samson-post, showing the attachment of my invention thereto; Fig. 4 is a plan view of the arrangement shown in Fig. 3; Fig. 5 is a further enlarged sectional elevation of the temper screw; Fig. 6 is a detail plan view of one of the bearing blocks, the view being taken on line 6—6 of Fig. 2; Fig. 7 is a detail view of the mounting for one 100 of the adjusting sprockets, being taken as indicated by line 7—7 of Fig. 3; and Fig. 8 is a sectional view of the sprockets and mounting therefor, taken as indicated by line 8—8 of Fig. 4. 105

Referring now to the drawings, and particularly to Figs. 2, 5 and 6, my invention comprises essentially a main screw 10, revolvably journaled at its upper end in a T-bearing 11, and carrying a bearing block 12 on which are supported supporting rods 13, constituting the frame, to the lower end of which a yoke 14 is rigidly secured, for supporting a suitable line engaging clamp, generally designated by the numeral 15.

The screw 10 may be of any length and diameter desired for accomplishing the work, and the threads may be of any size sufficiently heavy to carry the load of the line. The upper end is turned smooth, as at 15^a, forming a bearing portion extending loosely through a bore 16, in the lower bearing portion 17, of the T-block 11, the upper end 18 being enlarged, as shown, to form a shoulder 19 (see Fig. 5). A thrust bearing, generally designated by the numeral 20, may be interposed between the shoulder 19 and the top face 22 of the portion 17, this bearing being of any nature suitable to carry the load imposed upon the screw, and at the same time permit its free rotation. The bearing shown will accomplish this purpose in a satisfactory manner; and consists of a pair of opposed annular plates 23 and 24, having central apertures through which the bearing portion 15^a extends, and being annularly grooved for the retention of balls 25. A nut 26 may be screw-threadedly mounted on the screw 10, to abut against the lower face 27, of the portion 17, to limit the longitudinal movement of the portion 15 in this bearing.

The bearing block 12, is preferably of the configuration shown in the drawings, and has a central longitudinal bore 28, internally screw-threaded for engaging the screw-threads of the screw 10, and a pair of smaller bores on either side thereof, designated by the numeral 29, through which the supporting rods 13 extend. The supporting rods 13 have heads 30 which may be formed integral therewith, or may have screw-threaded connections, as shown in the drawings adapted to engage the top face of the block 12, to support them therein, or any other suitable form of means may be provided for rigidly securing them in their supported positions.

A second bearing block 31 is provided having a central bore 32, and a pair of bores 33 on either side thereof, through which the supporting rods 13 loosely extend; this block being provided primarily for the purpose of holding the lower end of the screw 10 in alignment with the rods 13. It is typical of the block 12, with the exception that the central bore 32 is smaller than the bore 28, and it is not internally screw-threaded to engage the rod 10; but has a smooth bore for the reception of the

lower reduced end 34, and is slidably carried on the supporting rods 13, by means of a nut 35 screw-threadedly mounted on the reduced end 34 as shown. If desired, the lateral ends of the block 31 may be transversely slotted into the bores 33, and lugs 36 provided thereon, for the reception of screws 37, whereby the half portions 31^a will act as spring clamps, which may be clamped about the supporting rods 13, to take up some of the load of the line when permissible.

The yoke 14 may be secured to the supporting rods 13, in any suitable manner and I have here shown the latter as extending through vertical bores 38 therein, and as having nuts 39, screwthreadedly engaging the lower ends to support the yoke thereon. However, if desired the lower ends of the rods 13 may be welded, or otherwise brought together, forming a swivel, on which the yoke may be supported in the manner heretofore employed.

The T-bearing 11 comprises the lower bearing portion 17, having a pair of upwardly extending arms 40, terminating in trunnions 41, by means of which the screw is pivotally mounted upon the walking-beam 42. In ordinary practice the trunnions 41 are merely supported in grooves cut in the top faces 43 of the outer ends of the individual members 42^a comprising the walking beam 42, so the screw hangs down between them, and this method of mounting may be utilized in the mounting of my device. However, I prefer to use a pair of typical bearing blocks 44, rigidly mounted on the top faces of the walking beam members, (see Figs. 2 and 3), in which the trunnions 41 are pivotally journaled, to properly support the parts to be hereinafter described, in operative relation to the walking beam. Thus it will be seen that the T-head 11 is mounted upon the walking beam 42, so the screw will pivot in a plane therewith, during the vertical reciprocating movement of the end thereof, and that the screw 10 is rotatable relative thereto. In order that the bearing block 12, and the supporting rods 13, carrying the clamp 15, will not be rotated with the screw 10 when it is rotated, I provide a guide rod 45, which extends through a bore 46 in a lug 47, on the portion 17 of the T-block 11; this rod also passing loosely through a bore 48 in an outwardly extending lug 49, on the block 12; and through a similar bore 50 in a similar lug 51, on the block 31. Nuts 52 may screw-threadedly engage the ends of the rod 45, to retain it in the lugs 47 and 51, as described.

A sprocket wheel 53, is rigidly mounted upon the upper end of the enlarged portion 18, of the screw 10, for rotating the

screw 10 in the bearing portion 17; this sprocket being adapted to be rotated by a suitable chain 54, engaging it and a similar but larger sprocket 55, mounted upon the walking beam 42 (see Figs. 3 and 4). The sprocket 55 is mounted to rotate in a horizontal plane with the sprocket 53, and parallel with the top face of the walking beam, on a vertically disposed shaft 56, being keyed thereto, which shaft in turn is revolvably mounted in a suitable bearing upon a support 57.

The sprocket 53 is mounted on the screw 10 in axial alignment with the trunnions 41, to minimize, as far as possible, any variation in distance between the axis of the screw and the shaft 56, when the screw is swinging relative to the walking beam during operation; and the sprocket 55 is mounted to rotate in a plane with the sprocket 53, when the walking beam is in horizontal position. However, as the plane of rotation of the sprocket 53 will vary relative to the top face of the walking beam during operation, some means must be provided to compensate for it. This I accomplish by providing a pair of tubular bearings 58 on either end of the support 57; these bearings being slidable on bearing rods 59, which in turn are rigidly supported in suitable brackets 60, on the top faces of the walking beam members 42^a. Expansile wire springs 61, surrounding the rods 59, and confined between brackets 60 and bearing sleeves 58, serve to hold the chain 54 taut, during all variations in relative positions of the screw 10 and shaft 56, permitting such movements, while at the same time maintaining an operative engagement at all times with the sprockets 53 and 55.

The screw 10 is adapted to be manually rotatable, through the medium of the sprocket 53, chain 54, sprocket 55 and shaft 56, by means of an endless chain 62, engaging a second sprocket 63, likewise keyed upon the shaft 56; this second chain 62 passing over guide rollers 64, supported upon the top of the walking beam members 42^a, and hanging downwardly to a point adjacent the floor 65, of the rig 66, and in position where it can be reached by a workman standing on this floor. In order that the chain 62 will not run off the rollers 64, during operation of the walking beam 42, these rollers are provided with suitable guides or housings 65, as is also the sprocket 63, as indicated at 66.

In operation it will be readily seen that a workman, standing upon the floor 65 adjacent the casing head 67, where he is in position to keep his hand on the line 68, to feel the drills striking the bottom of the bore, can keep hold of the chain 62, and, through the medium of this chain, the sprocket 63, shaft 56, sprocket 55, chain

54, and sprocket 53 on the upper end of the screw 10, properly feed out the screw and consequently the line into the bore during operation of the walking beam 42.

Various modifications and rearrangements in structure may be made, from that shown in the drawings, as for instance the arrangement of sprockets and chains for operatively rotating the screw 10 during operation of the walking beam 42, may be altered to suit circumstances, and many other types of operating means may be provided for accomplishing the desired results. And, while I have herein disclosed the preferred embodiment of my device, to accomplish the desired end, it is nevertheless to be understood that I do not wish to limit myself to these particular structural features as shown, but reserve the right to make any changes or modifications in structure which will come within the scope of the appended claims.

Having described a preferred form of my invention, I claim:

1. In a device of the character described, a bearing member, a screw member revolvably supported at its upper end in said bearing member, a bearing block screw threadedly mounted on the screw, a frame carried by the bearing block, and means to prevent rotation of the frame with the screw, said means comprising a rod carried by the bearing member and slidably engaged by the bearing block. 90

2. In a device of the character described, a bearing member, a screw member revolvably supported at its upper end in said bearing member, a bearing block screw threadedly mounted on the screw, a frame carried by the bearing block, a guide block to keep the screw in alignment with the frame, and means to prevent rotation of the frame with the screw, said means comprising a rod carried by the bearing member and guide block and slidably engaged by the frame. 100

3. In a device of the character described, a bearing member, a screw member revolvably supported at its upper end in said bearing member, a bearing block screw threadedly mounted on the screw, a frame carried by the bearing block, a guide block carried by the screw and slidably engaging the frame to keep the screw in alignment with the frame, and means to prevent rotation of the frame with the screw, said means comprising a rod carried by the bearing member and guide block and slidably engaged by the frame. 110

4. In a device of the character described, a bearing member, a screw member revolvably supported at its upper end in said bearing member, a frame movably carried on said screw member, said frame having a bearing member at its upper end screw 120

- threadedly engaging the screw, a guide block revolvably carried by the lower end of the screw and slidingly engaged by the frame to keep the screw in alignment therewith, and means to prevent rotation of the frame with the screw, said means consisting of a guide rod carried between the bearing member and the guide block and slidingly engaged by the frame.
- 5 10 5. In a device of the character described, a bearing member, a screw member revolvably supported at its upper end in said bearing member, a bearing block screw threadedly mounted on the screw, a frame carried by the bearing block, means to prevent rotation of the frame with the screw, said means comprising a rod carried by the bearing member and slidingly engaged bearing block, and means to rotate the screw to cause longitudinal movement of the frame thereon.
- 15 20 6. In a device of the character described, a bearing member, a screw member revolvably supported at its upper end in said bearing member, a bearing block screw threadedly mounted on the screw, a frame carried by the bearing block, a guide block to keep the screw in alignment with the frame, means to prevent rotation of the frame with the screw, said means comprising a rod carried by the bearing member and guide block and slidingly engaged by the frame, and means to rotate the screw to cause longitudinal movement of the frame thereon.
- 25 30 35 7. In a device of the character described, a bearing member, a screw member revolvably supported at its upper end in said bearing member, a bearing block screw threadedly mounted on the screw, a frame carried by the bearing block, a guide block carried by the screw and slidingly engaging the frame to keep the screw in alignment with the frame, means to prevent rotation of the frame with the screw, said means comprising a rod carried by the bearing member and guide block and slidingly engaged by the frame, and means to rotate the screw to cause longitudinal movement of the frame thereon.
- 40 45 50 8. In a device of the character described, a bearing member, a screw member revolvably supported on said bearing member, a bearing block screw threadedly mounted on the screw, a frame carried by the bearing block, and means carried by the bearing member to prevent rotation of the frame with the screw.
- 55 60 65 9. In a device of the character described, a bearing member, a screw member revolvably supported on said bearing member, a bearing block screw threadedly mounted on the screw, a frame carried by the bearing block, and means carried by the bearing member and engageable by the bearing block

to prevent rotation of the frame with the screw.

10. In a device of the character described, the combination with a vertically movable member, of a bearing member mounted thereon to rotate about a horizontal axis, a screw member carried by the bearing member and adapted to rotate about a vertical axis, a frame screw threadedly mounted on the screw to carry a drill line, means to prevent rotation of the frame with the screw, and flexible means operatively connected with the screw to rotate it to feed out the line.

11. In a device of the character described, the combination with a vertically movable member, of a bearing member mounted thereon to rotate about a horizontal axis, a screw member carried by the bearing member and adapted to rotate about a vertical axis, a bearing block screw threadedly mounted on the screw, a frame carried by the bearing block, means carried by the bearing member to prevent rotation of the frame with the screw, and means to rotate the screw, said means being flexible to compensate for pivotal movement of the screw about its horizontal axis.

12. In a device of the character described, the combination with a walking beam, of a bearing member mounted thereon to rotate about a horizontal axis, a screw member carried by the bearing member and adapted to rotate about a vertical axis, a bearing block screw threadedly mounted on the screw, a frame carried by the bearing block to support a drill line, means carried by the bearing member and engageable by the bearing block to prevent rotation of the frame with the screw, and means carried by the walking beam for rotating the screw to feed out the line, said means embodying a flexible operative connection with the screw to compensate for its movement about its horizontal axis.

13. In a device of the character described, a bearing member, a screw member revolvably supported by said bearing member and held against relative axial movement, a bearing block screw-threadedly mounted on the screw, a frame carried by the bearing block for supporting a drill line, and means to prevent rotation of the frame with the screw.

14. In a device of the character described, a bearing member, a screw member revolvably supported by said bearing member and held against relative axial movement, a bearing block screw-threadedly mounted on the screw, a frame carried by the bearing block for supporting a drill line, and means in connection with the bearing member to prevent rotation of the frame with the screw.

15. In a device of the character described,

the combination with a vertically movable member, of a bearing member mounted thereon to rotate about a horizontal axis, a screw member carried by the bearing member and adapted to rotate about a vertical axis but held against axial movement relative thereto, a frame screw-threadedly mounted in the screw to carry a drill line, means to prevent rotation of the frame with the screw, and means operatively connected with the screw to rotate it to feed out the drill line.

16. In a device of the character described, the combination with a walking beam, of a bearing member mounted thereon to oscillate about a horizontal axis, a screw member

carried by the bearing member adapted to rotate about a vertical axis but held against axial movement relative thereto, a frame screw-threadedly carried by the bearing block to support a drill line, means carried by the bearing member and engageable by the frame to prevent rotation of the frame with the screw, and means carried by the walking beam for rotating the screw to feed out the line, said means embodying a flexible operative connection with the screw to compensate for its oscillatory movement.

In witness that I claim the foregoing I have hereunto subscribed my name this 23d day of March, 1921.

LESLIE E. WRIGHT.
